PLANT FOR WASHING COAL AND OTHER MINERALS

Filed Nov. 7, 1927

UNITED STATES PATENT OFFICE

ANTOINE FRANCE, OF LIEGE, BELGIUM

PLANT FOR WASHING COAL AND OTHER MINERALS

Application filed November 7, 1927, Serial No. 231,650, and in Belgium March 4, 1927.

The present invention relates to an improvement in plants for washing coal and other minerals of the type wherein the latter are sorted, in order of their respective densities, inside one or more horizontal or slightly inclined launders, this sorting being effected by the action of an alluvium forming stream, whereby the light particles are driven into the upper layers while the dense particles are sent down towards the bottom parts of the launder or launders, which are provided with slots for the reception of the dense particles so sent down. Now, to avoid the falling of light particles through the slots, which are intended for conveying away a material the density of which should reach at least a given minimum, it is desirable that the layer of dense material which is upstream with relation to these slots shall be freed from its light particles, and shall be of a sufficient and uniform thickness to avoid the liability of the light particles being driven into the slot simultaneously with the dense products. It is further desirable that the materials which are to pass over and beyond the last slot, shall be sufficiently cleansed, i. e. sufficiently freed from any particles of another class and detrimental to them. Now, the circumstances which prevail during the classification are liable to vary with the general shape of launder section; it will accordingly be adequate to make the effective section of the launder at all points of a configuration which has been judiciously determined so as to ensure that the various stages of the operation follow each other in such sequence as to obtain the desired classification. On the other hand, as both quality and quantity, or the nature of the material, are liable to frequent changes, it is of great avail to provide for the possibility of easily regulating the shape of the section, and as it is particularly desirable to secure a favourable shape for the lower layers of dense material, the advantage will lie in the possibility of more judiciously shaping that portion of the launder section which is nearest the bottom. The present invention has for its object to provide a mechanical adjustment of the effective section of the launder, and comprises devices permanently located in the launder and movable transversely of the launder, to allow the section of the launder to be adjusted in the lower parts thereof. The invention also includes devices for this purpose embodying a set of plates or false sides forming a combination of movable surfaces of variable inclination and direction, capable of modifying the section of the launder in such a manner that the shapes of plan sections made at different levels are variable. The invention further includes the various details and embodiments herein-after described.

In the accompanying drawings, Figures 1 and 2 are respectively a cross section and a sectional plan of a portion of launder equipped at both sides with a device for adjusting its width; Figure 3 is a diagrammatic sectional plan illustrating a portion of launder wherein an adjustment of the effective section is secured by the employment of a particular arrangement of several movable slides; Figure 4 is a diagrammatic sectional plan showing a length of launder wherein a movable slide consists of two parts capable of sliding longitudinally one upon the other; Figure 5 is a sectional plan showing a modification wherein an end of a portion of slide is overlapped by the corresponding end of the next portion of slide. Fig. 6 is a longitudinal vertical sectional view of the launder, showing the slots (of known type) and the slides. Fig. 7 is a transverse vertical sectional view on line VII—VII of Fig. 6. With reference to Figures 1 and 2, the device according to this invention for the purpose of adjusting the width of the launder or portion of launder 1 consists of two lateral plates or false sides 2 extending upwards and so bent at their lower ends as to form flanges 3, which rest upon the launder bottom. These plates 2 can be shifted transversely of the launder 1 by means of screws 4 each of which traverses a screw-threaded hole 5 in the corresponding side of the launder. Each plate 2 is connected at its upper edge by a hinge 6 to a second plate 7, the

upper edge of which rests against the inside face of the corresponding side of the launder 1. The screws 4 are so connected to the plates 2 that they can be turned relatively to them, rotation of the screws resulting in axial motion thereof and causing the plates 2 to move and, therefore, to alter the effective width of the launder.

This movement of the lower plates 2 is transmitted through the hinges 6 to the upper plates 7, the upper edges of which slide on the inner surface of the sides of the launder 1.

It will be readily understood that the adjustment of the channel width by means of the arrangement just described can easily take place whilst the washing plant is in operation.

The arrangement illustrated in Figure 3 is a combination of movable slides, which is shown here by way of an example, to explain an arrangement whereby particularly favourable conditions will prevail for securing, upstream of every slot 9, a bedding of dense material having a sufficient thickness and homogeneity to prevent any light particles, which travel above this bedding, escaping down with the dense particles into the slot 9 and the discharge, packet 10 arranged beneath the slot, and to still increase, on their passing these slots, the difference in the speed at which the light and the dense particles are respectively driven along the launder bottom.

Such an arrangement will enable the following results to be obtained; in the stage from A to B, an increasing thickness of the layer of dense material moved along the launder bottom, owing to the section getting narrower and narrower;—then, from B to C, the layer of dense material has its thickness regularized owing to the uniform section of the launder; the operator can thereby avail himself of all the conditions favourable to the obtaining of an evacuation of dense material freed from any light particles, since he gets, in front of the slot, a layer of dense material of a sufficiently uniform thickness, in addition to which is to be noted that the light particles are the better separated from the dense material bedding as they are driven away at a higher rate of speed upstream and above the device, owing to the launder getting narrower and narrower, at these points;—from C to D, he will have the advantage of a depositing of the dense particles which would be dragged along in the upper part of the stream, under co-operation of the spreading of the material together with the decrease in the speed at which the stream passes, due to the widening of the launder in the direction of its length;—from D to E the layers get more regularly formed, for the effective section of the launder is there uniform throughout the length of launder considered;—then, from E to F, the

dense material layer gets thicker while fostering separation of the light particles which are driven along together with the dense particles.

Means such as screws 4 or the like have been provided for adjusting the position of the movable slides and for modifying the shape of the effective section of the launder if such modification be needed, say, for example, in the event of some change in either quality or quantity of the material being dealt with.

The movable slides are generally vertical i. e. perpendicular to the bottom of the launder and one slide is connected to the other by hinges illustrated in A, B, C, D, E, F. On turning the screw 4 to the left, the plate B C is pulled back and the end D' of the adjacent plate C D' slides in the slide-way integral with the next plate D D', whilst the other adjacent plate A B acting as a connecting rod, pushes the plate A A' forward, making it slide in a slide-way A' integral with the side of the launder. Similarly, the turning of the screw 4' causes plates D E, D D', E E' to move, as also the sideways D', E' integral with the two last-named plates and the ends of plates C D' and F E' to slide in these slideways. These last slide-ways may consist of two plates parallelly mounted on the edges of the slide.

The movable slides may be of more complicated types, more particularly the type illustrated by Fig. 1 may be applied to them. In this case the lower plates 2 of two consecutive movable slides may be connected by hinges.

In the embodiment shown in Figure 4, the false sides or lateral partitions of the length of launder considered can consist of two parts 2 and 2' capable of sliding one upon the other in such a manner as to move, for example, from the position shown in full lines to that shown in dotted lines. An arrangement of this kind can be useful if, for example, the operator has to adjust that length of the launder wherein the section remains uniform but also adjustable in width. According to the needs prevailing at the time, it will be advisable to use either slides or movable plates, the sizes of which will be regulated in such a manner as to result in suitable modifications in the shape of the length of launder considered.

In Fig. 4, the movable slides or plates, which are again generally perpendicular to the bottom of the launder, are connected in 8 to the sides of the launder. When the plates 2 and 2' are moved either longitudinally or transversely of the launder, the sides of the launder move with them and slide in slide-ways having the screwholes 5 formed therein. The type illustrated by Fig. 1 can also be applied in this case, in the same way as described for Fig. 3.

To avoid any solid particles penetrating

the junction of two length of slides, while they are being moved, the edge of one slide may overlap the adjacent edge of the next succeeding slide, for instance, as illustrated in Figure 5, wherein the ends 11 and 11' of two slides 2''' and 2''' are rabbeted and machined so as to accurately fit each other.

It should be understood that the devices hereinbefore described are mere examples of practical embodiments of the present way of securing the adjustment of the effective section of the launder, and it should be noted that such adjustment can be arrived at by resorting to any similar means; similarly, the invention is not confined to a symmetrical arrangement, since the provision of movable plates may be restricted to one side only of the launder; likewise, the control of the adjustment by means of screws has been stated merely by way of example intended for facilitating comprehension of the description, and it should be understood that the control can be effected by any other means.

I claim:

1. In plants for washing coal and other minerals, comprising a launder in which the products are classified according to their specific gravity under the action of a liquid conveying stream and in the bottom of which are arranged slots for delivering the products which move in the bottom part of said launder: baffles extending at right angles from the bottom of the launder to a level inside said launder, baffles at an angle with the first-mentioned baffles and connected at one of their ends to said first-mentioned baffles and resting at their other ends upon the lateral sides of the launder, means to adjust the position of the first-mentioned baffles inside the launder, thereby adjusting the width of the bottom portion of the launder.

2. In plants for washing coal and other minerals, comprising a launder in which the products are classified according to specific gravity, under the action of a liquid conveying stream, and in the bottom of which are arranged transverse slots for discharging the products which move in the bottom part of said launder: a series of partitions extending inside the launder at right angles from the bottom thereof and parallel to the sides thereof, a series of partitions extending inside the launder at right angles from the bottom thereof and each connecting two partitions extending parallel to the sides, the arrangement being such that all the partitions cooperate to form at least one uninterrupted false side to be applied to a lateral side of the launder over a substantial length thereof, and means to independently move said first-mentioned partitions transversely of the launder.

3. In plants for washing coal and other minerals, comprising a launder in which the products are classified according to specific

gravity, under the action of a liquid conveying stream, and in the bottom of which are arranged transverse slots for discharging the products which move in the bottom part of said launder: a series of partitions extending inside the launder at right angles from the bottom thereof to form at least one uninterrupted false side to be applied to a lateral side of the launder, the arrangement being such that the inner section of the launder varies in the downstream direction, so as to comprise consecutively a portion gradually widening from a point located downstream of a slot, a relatively wide portion of constant section, a portion gradually narrowing up to a point located upstream of the next slot, a relatively narrow portion of constant section extending from a point upstream to a point downstream of said last-mentioned slot, and means to independently move transversely of the launder the partitions forming the said portions of constant section.

4. In plants for washing coal and other minerals, comprising a launder in which the products are classified according to specific gravity, under the action of a liquid conveying stream, and in the bottom of which are arranged transverse slots for discharging the products which move in the bottom part of said launder: partitions extending longitudinally inside the launder at right angles from the bottom thereof to form at least one uninterrupted false side to be applied to a lateral side of the launder over a substantial length thereof, means to move a number of said partitions transversely of the launder, and means to move a number of said partitions longitudinally of the launder.

5. In plants for washing coal and other minerals, comprising a launder in which the products are classified according to specific gravity, under the action of a liquid conveying stream, and in the bottom of which are arranged transverse slots for discharging the products which move in the bottom part of said launder: partitions extending longitudinally inside the launder at right angles from the bottom thereof, to form at least one uninterrupted false side to be applied to a lateral side of the launder over a substantial length thereof, means to move a number of said partitions transversely of the launder, parts at the ends of a number of partitions overlapping similar parts at the end of adjacent partitions, and means to move a number of partitions longitudinally of the launder, so as to vary the length of the said parts overlapping each other.

6. In plants for washing coal and other minerals, comprising a launder in which the products are classified according to specific gravity, under the action of a liquid conveying stream, and in the bottom of which are arranged transverse slots for discharging the products which move in the bottom part of

said launder: a series of partitions extending inside the launder at right angles from the bottom thereof and parallel to the sides thereof, a series of partitions extending inside the launder at right angles from the bottom thereof and each connecting two partitions extending parallel to the sides; a third series of partitions at an angle with the partitions of the two first series and connected at one of their ends to said partitions of the first two series and resting at their other ends upon the lateral sides of the launder, means to independently move said first mentioned partitions transversely of the launder, there-
by altering the inclination of the partitions of the second and third series.

In testimony whereof I signed hereunto my name.
